E. J. Shuey

A technical drawing of a mechanical assembly. It features two vertical rectangular supports. A horizontal beam is positioned between them, with a central section that appears to be a threaded rod or a bolt. The ends of this central beam are attached to the vertical supports. There are small circular features at the junctions where the beam meets the supports.

UNITED STATES PATENT OFFICE.

THOMAS G. SMITH, OF NEW ORLEANS, LOUISIANA.

ANTIROBBERY AND BURGLAR-PROOF CAR.

1,089,506.

Specification of Letters Patent. Patented Mar. 10, 1914.

Application filed May 31, 1913. Serial No. 770,930.

To all whom it may concern:

Be it known that I, THOMAS G. SMITH, citizen of the United States, residing at New Orleans, in the parish of Orleans and State 5 of Louisiana, have invented new and useful Improvements in Antirobbery and Burglar-Proof Cars, of which the following is a specification.

My present invention pertains to express 10 cars.

The object of the invention is to provide an anti-robbing and burglar-proof car, embodying such a construction that the carrying capacity of the car is practically undiminished and yet a guard is enabled to effectively resist robbers and prevent them from gaining access to the more valuable portion of the matter carried in the car, even if they gain access to the lower apartment in which 20 ordinary express matter is carried.

The invention also contemplates making the whole of the car body of steel and the utilization of the upper apartment in its entirety as a safe, thus rendering it unnecessary 25 to increase the weight of the car and the cost of transporting valuables by providing safes or vaults to hold the same, the valuables, on the other hand, being placed in boxes, pigeon holes or other means provided 30 for their reception and built when desired in the apartment.

The invention further contemplates the provision of a car having a lower apartment and an upper apartment, and also having 35 means calculated to enable a guard or guards in the upper apartment to prevent a robber from entering the lower apartment and to also effectively resist the passage of a person from the lower apartment to the upper 40 apartment, this latter being advantageous in the event that a person surreptitiously gains access to the lower apartment or the attendant or attendants in said apartment prove dishonest.

Other advantageous characteristics of the 45 invention will be fully understood from the following description and claim when the same are read in connection with the drawings, accompanying and forming part of this 50 specification, in which:

Figure 1 is a horizontal section taken through the upper apartment of the car body constituting the best practical embodiment of my invention that I have as yet devised, and showing the horizontal partition

wall and its appurtenances in plan. Fig. 2 is a vertical transverse section of the car.

Similar numerals and letters of reference 60 designate corresponding parts in all of the views of the drawings.

The body of my novel car is preferably constructed of steel, and is divided by a horizontal partition wall 1 into a lower apartment 2, and an upper apartment 3. The lower apartment is preferably of a 65 slightly greater height than the upper apartment, and said lower apartment is, by preference, provided with side doors *a* and end doors *b*. In the lower apartment is designed to be carried ordinary express packages or 70 matter such as ordinarily is not of great value, and is therefore not likely to excite the cupidity of robbers.

The upper apartment 3 is designed to carry currency, jewelry, bullion and other 75 valuables, and in this connection it will be noted that notwithstanding the upper apartment can be effectually isolated from the lower apartment, the provision of the said upper apartment does not detract to an ap- 80 preciable extent from the carrying capacity of the car; and it will also be noted that one or more express messengers or guards can be disposed and comfortably accommodated in the upper apartment. In the side walls of 85 the upper apartment 3, window openings 4 are provided, and these openings are preferably barred or latticed as shown, and are further controlled by slidable shutters 5 of 90

It will be manifest that the upper apartment 3 being formed by steel walls, and being adapted as hereinafter described in detail, to be completely isolated from the lower apartment, is in itself a steel safe, and that 95 therefore it is not necessary precedent to placing valuables in said apartment for transportation to store the valuables in heavy safes. On the other hand, the valuables can be placed in pigeon holes or other 100 compartments provided in the apartment 3, or if desired the valuables can be packed in small boxes or can be carried in bulk in the said apartment.

In the central portion of the partition 105 wall 1, an opening 6 is provided, the said opening being designed to enable a guard to pass from the lower apartment to the upper apartment and vice versa and being also designed for the passage of valuables to and 110

from the upper apartment 3. The opening 6 is controlled by a steel door 7, and said door 7 is disposed in a guideway 9, calculated to effectually prevent raising thereof. 5 I would also have it understood that any suitable means, such as a conventional lock (not shown) may be employed to secure the door 7 in its closed position; the said lock being of course under the control of a guard 10 located in the apartment 3.

In addition to the opening 6, the partition wall 1 is provided with small openings 10, controlled by slidable doors 11, disposed in guideways 12. There is one of the said 15 small openings 10 above and adjacent each door complementary to the lower apartment 2, and each opening 10 is only large enough to enable the guard or guards in the upper apartment to command by gun play 20 the doors *a* and *b* of the lower apartment.

It will be gathered from the foregoing that my novel car is constructed to afford protection and safety from robbery from within, on the part of the employees in the 25 lower apartment, for instance, as well as from without by holdup-men or train robbers.

Having described my invention, what I

claim and desire to secure by Letters-Pat-
ent, is:

An anti-robery and burglar-proof car 30 body divided by a horizontal partition into lower and upper apartments that extend throughout its area and are free of obstruc-
tion, and having doors in the side walls of 35 one apartment and also having a large central opening in the partition wall and small openings in said partition wall located ad-
jacent the first-named doors, horizontally 40 slidable doors for controlling said openings in the horizontal partition, and guideways on said partition constructed and arranged 45 to prevent vertical movement of the doors; the apartment other than the one having doors in its side walls being constructed and arranged to accommodate a guard and prevent entrance to the apartment except through the central opening in the partition.

In testimony whereof I have hereunto set 50 my hand in presence of two subscribing wit-
nesses.

THOMAS G. SMITH.
